UNITED STATES PATENT OFFICE.

ERNI J. KNOWLTON, OF BIRMINGHAM, ALABAMA.

SWITCH-OPERATING MECHANISM.

1,061,185.

Specification of Letters Patent.

Patented May 6, 1913.

Application filed September 8, 1911. Serial No. 648,262.

To all whom it may concern:

Be it known that I, ERNI J. KNOWLTON, a citizen of the United States, and a resident of Birmingham, in the county of Jefferson 5 and State of Alabama, have invented certain new and useful Improvements in Switch-Operating Mechanism, of which the following is a specification.

This invention is an improvement in 10 switch operating mechanism and particularly in that class of such mechanism wherein the devices for moving the switch are operated from a moving locomotive or car and the invention consists in certain novel 15 constructions and combinations of parts as will be hereinafter described and claimed.

In the drawings Figure 1 is a top plan view of a track way provided with my improvements. Fig. 2 is a detail longitudinal 20 section on about line 2—2 of Fig. 1. Fig. 3 is a cross section on about line 3—3 of Fig. 1. Fig. 4 is a cross section on about line 4—4 of Fig. 2. Fig. 5 is a detail bottom plan view, partly in section, showing the cam, the drums and the means for operating the cam by hand. Fig. 6 is a detail longitudinal section showing the devices in the 25 track way and the operating devices on the locomotive or car. Fig. 7 is a detail cross 30 section illustrating the devices for operating the moving parts in the track way. Fig. 8 is a top plan view illustrating a construction wherein the switch point is operated directly from the cam.

35 In the construction shown in Fig. 1, the operating means are connected to a single switch point A, but it will be understood that where two opposite switch points are employed with a bar between them, the devices 40 may be connected to such connecting bar to operate both switch points. As shown in Fig. 1, a lever B is connected at its front end to the switch point A, is pivoted between its ends at B' and extends at its rear 45 end into a cam groove C' in a cam pulley C. This groove C' has two circumferential portions C² diametrically opposite each other and in which the lever B rests both when the switch point is open and closed so that in 50 such position of the switch point any accidental movement of the switch point or strain on the switch point, will not operate through the cam to move the operating devices. The lever B has sufficient spring to 55 enable the flange of a car coming from the left in Fig. 1 to pass between the switch

point and the rail. The cam C is on a shaft D and this shaft is also provided with drums E and E' spaced apart and fixed to the shaft D so they may be moved to turn the shaft D 60 in the operation of the device.

If used on steam railroads, the shaft D may be provided with a bevel gear D' which is meshed by a bevel gear F' on a switch shaft F, which shaft F is supplied with a 65 suitable semaphore F² and is also provided with a handle F³ by which it may be turned. This handle F³ operates within a keeper F⁴ and at its initial movement operates to depress a rod G whose lower end connects with 70 one end of a pivoted lever H whose other end bears below a locking bar I, which operates in the manner presently described. It will be noticed that if one or the other of the drums E, E' be turned, it will correspondingly turn the shaft D and by preference, I 75 roughen the drums by corrugation or otherwise so they can be conveniently operated by an operating device in the form of a shoe depending from the train equipment and these drums E and E' are provided with flattened portions E¹⁰ and E¹¹, those of the two drums being arranged diametrically opposite each other so that the flattened portion of one drum will be uppermost 80 while the flattened portion of the other drum will be at the bottom thereof, as will be understood from Figs. 1, 4 and 5 of the drawings.

To prevent the drums from accidental 85 movement, I provide the shaft above and below its axis with parts D² in the form of bars extending between the drums E and E' and which enter a notch I' in the locking bar I, the said bar I being pivoted at I² and 90 weighted at its front end I³ so it will normally drop into engagement with the co-operating part on the shaft D. In the operation of the switch handle F³, the bar I³ can be released prior to the turning of the 95 shaft D by the aid of the shaft F, but for releasing the locking bar I from a moving train, I prefer to employ the rockers J and J' aligned with their respective drums E and E' and connected by a rod J², which bearing upon the rear end of the locking bar I 100 when the rockers are tilted from the position shown in Fig. 2, operates to release the locking bar. The rockers are weighted at J³ so they normally assume the position 105 shown in Fig. 2, but where necessary or desirable, the springs J⁴ may be arranged as 110

shown in Fig. 2, to supplement the gravity of the rockers. When the parts are as shown in Fig. 2, it is manifest the drums cannot be turned to operate the cam C until the locking bar has been released and in the operation of the device by a shoe from a moving train, the said shoe will first bear upon the upper end of the rocker J or J' and will then engage with the drum E or E' to turn the same to move the cam and thus operate the switch point either to open or closed position as the case may be. It will also be noticed that the movement of the drums E and E' and consequently of the shaft D is always in the same direction, there being no reciprocal movement of the shaft. It may, in some instances, be desirable to omit the lever B and operate the switch point directly from the cam C and this may be accomplished by the construction shown in Fig. 8 of the drawings.

When the device is in use on a street railroad and it is desired to operate the switch apart from a moving car, the shaft F being omitted ordinarily on street railroads, the switchman can operate the rocker J with one foot to release the locking bar I and then move the corresponding drum with his other foot or with a suitable push bar as may be desired. I prefer, however, to provide for operating the switch from a moving train and I illustrate in Fig. 6 a construction for this purpose. In this construction, a treadle K operates a bell crank lever L which by a rod M operates toggles N, spring actuated at N' and carrying at their lower ends a shoe O which can be depressed as shown in Fig. 6 to operate the rocker and the drum in alinement therewith or can be raised to the dotted line position to clear their respective rockers and drums, a spring M' on the rod M coöoperating with the springs N' in securing this result. The spring M' aids in this operation by exerting a longitudinal tension on the rod M. The spring M' is a tension spring tending to bend the toggle and so elevate shoe O and pedal K. The spring N' is intended to overcome the up and down motion of the car and prevent a heavy jar on the rocker O; also to allow the rocker O to pass over any small obstacle in the street and also to permit the rocker O to mount the drum E in passing over it.

Manifestly in the use of the invention, the operator on the car or locomotive will lower the appropriate shoe O to engage with the drum E or E' which he may desire to operate to throw the switch either to open or closed position as may be desired. It will be noticed that the cam groove is so gradual that no serious jar will be exerted upon the parts should the drums be operated by a rapidly moving train and that the circumferential portions C² of the cam grooves will lock the switch point in such manner that a

wagon or other device striking upon the switch point will not act to automatically throw the switch from the position in which it may be adjusted.

The invention is simple, easily operated and efficiently serves the purpose for which it is designed.

It will be noticed that a pawl and ratchet P, see Fig. 1, is arranged between the handle and the switch shaft, so that the semaphore may be operated with all operations of the switch point without disturbing the switch handle when the automatic operation is taking place.

I claim:

1. The combination substantially as herein described, of a switch point, a lever to operate said point, a cam operating said lever, a pair of drums operating said cam, means for locking said drums from movement, devices for releasing said locking means to permit the operation of the cam by the movement of the drums, said releasing devices including rockers in alinement with their respective drums, a hand operating means connected with the cam for operating the same, and means operated by the hand operating means for releasing the drum locking means, all substantially as and for the purpose set forth. 80

2. The combination of a switch point, a cam for operating said point, means for operating said cam, a bar for locking said operating means from movement, and a rocker having means for releasing said locking bar 100 to permit the operation of the cam.

3. The combination of a switch point, a pair of drums each having a flat side with the flat side of one drum diametrically opposite that of the other, a pair of rockers in alinement with their respective drums, means for locking the drums from movement and arranged for operation by the rockers, and means whereby the drums may operate the switch point. 105

4. The combination of a switch point, a cam for operating the same and having diametrically opposite circumferential portions, a shaft having means for operating the cam whereby to operate the switch point, bars in connection with said shaft, a locking bar having at one end a notch operating in connection with said bar to lock the shaft from turning and a rocker for operating said locking bar, substantially as set forth. 115

5. The combination of a switch point, a rotating cam for operating the same, means for turning said cam step by step in the same direction for opening and closing the switch point, a locking bar pivoted between its ends and operating at one end to lock the cam from movement and a rocker operating upon the other end of the bar to release the same. 125

6. The combination with a switch point, a

pair of drums, and means whereby the turning of the drums may operate the switch point, of a locking bar for locking the drums from turning, and a pair of rockers having means for releasing said locking bar to permit the turning of the drums, substantially as set forth.

7. The combination with a switch point, a shaft having means for operating the switch point, and means for turning the shaft, of a lock for restraining said shaft from turning, a hand lever for turning the shaft by hand, and means operated by the said hand lever for releasing the shaft restraining lock.

8. The combination of a switch point, a cam having a groove, means operating in said groove for moving the switch point, the said groove having inclined portions, and

diametrically opposite circumferential portions, a drum moving intermittently in one direction for operating said cam, the said drum having a flat side whereby it may be operated by a shoe from above and the flat side will operate to stop the drum when moved to the desired extent.

9. The combination with a switch point, a drum having a flat side and intermediate devices whereby the turning of the drum will operate the point, of means for locking the drum from turning, and devices arranged for operation by a shoe from above and provided with means for releasing the lock, substantially as set forth.
